Patented October 11, 1904.

UNITED STATES PATENT OFFICE.

VERGIL C. BARBER AND WILL S. TURNER, OF CHICAGO, ILLINOIS.

DESIGN FOR A BADGE.

SPECIFICATION forming part of Design No. 37,161, dated October 11, 1904.

Application filed July 30, 1904. Serial No. 218,929. Term of patent 3½ years.

To all whom it may concern:

Be it known that we, VERGIL C. BARBER and WILL S. TURNER, citizens of the United States, residing at Chicago, in the county of Cook 5 and State of Illinois, have invented a new, original, and ornamental Design for Badges, of which the following is a specification, reference being had to the accompanying drawing, forming part thereof.

10 The figure is a plan view of a badge, showing our new design.

What we claim as new, and desire to secure by Letters Patent, is—

The ornamental design for a badge, as shown.

VERGIL C. BARBER.
WILL S. TURNER.
